UNITED STATES PATENT OFFICE.

WILLIAM H. LYNCHARD, OF COUNCIL BLUFFS, IOWA.

DESIGN FOR A BADGE.

SPECIFICATION forming part of Design No. 33,061, dated August 14, 1900.

Application filed June 29, 1900. Serial No. 22,079. Term of patent 3½ years.

To all whom it may concern:

Be it known that I, WILLIAM H. LYNCHARD, a citizen of the United States, residing at Council Bluffs, in the county of Pottawattamie and State of Iowa, have invented and produced a new and original Design for Badges, of which the following is a specification, reference being had to the accompanying drawings, forming part thereof, in which—

10 Figure 1 is a front elevation of my badge, and Fig. 2 a vertical central section of the same.

As shown in said drawings, my design consists of a representation of the palm of a hand, 15 as shown at A, having a scroll B running from the tip of the thumb to the tip of the little finger and adapted to receive a suitable inscription, the hand resting upon a shield C, representing the national escutcheon, and

this shield resting upon a scroll D. A garland E is supported from the hand and serves an ornamental purpose.

The essential or leading feature of my design consists in the representation of a hand and scrolls arranged as shown.

Having described my invention, what I claim as new, and desire to secure by Letters Patent, is—

The design for a badge, as herein shown and described.

In testimony whereof I hereby sign my name to this specification, in the presence of two subscribing witnesses, this 21st day of June, 1900.

WILLIAM H. LYNCHARD.

Witnesses:

D. E. STUART,
THOMAS BOWMAN.
